(57) **CLAIM**

The ornamental design for a riding mower, as shown and described.

DESCRIPTION

FIG. 1 a front perspective view of a riding mower showing our new design;

FIG. 2 is a rear perspective view thereof;

FIG. 3 is a front view thereof;

FIG. 4 is a back view thereof;

FIG. 5 is a top view thereof;

FIG. 6 is a bottom plan thereof;

FIG. 7 is a right side view thereof; and,

FIG. 8 is a left side view thereof.

The portions indicated in gray (dotted pattern) appearing at the back of the riding mower are portions at which a metal cover is perforated. The broken lines in the drawing views illustrate portions of the riding mower that form no part of the claimed design.
